US0D1031343S

(12) **United States Design Patent** (10) **Patent No.:** **US D1,031,343 S**
(45) **Date of Patent:** **** Jun. 18, 2024**

(54) **DISPENSER**

(71) Applicant: **PepsiCo, Inc.**, Purchase, NY (US)

(72) Inventors: **Martin Eduardo Broen**, New York, NY (US); **Stephen Lim**, Chappaqua, NY (US); **Christian Stolarz**, Brooklyn, NY (US); **Martin Ivar Franzen**, Milan (IT)

(73) Assignee: **PepsiCo, Inc.**, Purchase, NY (US)

(**) Term: **15 Years**

(21) Appl. No.: **29/825,722**

(22) Filed: **Feb. 4, 2022**

Related U.S. Application Data

(63) Continuation of application No. 29/725,132, filed on Feb. 21, 2020, now Pat. No. Des. 948,908, which is a continuation of application No. 29/653,586, filed on Jun. 15, 2018, now Pat. No. Des. 878,131.

(57) **CLAIM**

The ornamental design for a dispenser, as shown and described.

DESCRIPTION

FIG. 1 is a top front perspective view of a dispenser showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of a second embodiment thereof;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the figures show portions of the dispenser that form no part of the claimed design.

1 Claim, 14 Drawing Sheets
